UNITED STATES PATENT OFFICE.

JULIUS G. BURNS AND HERBERT S. DAVIS, OF NEW YORK, N. Y., ASSIGNEES TO
PURECOLD PRODUCTS OF AMERICA, INC., A CORPORATION OF DELAWARE.

FREEZING PRESS.

Application filed February 23, 1926. Serial No. 90,091.

This invention relates generally to presses of the manually operated type, the invention having more particular reference to an improved refrigerating press.

5 The object of the invention is the provision of an improved refrigerating press adapted to compress the solid form of carbon dioxide (CO_2) into suitable cartridges or containers.

10 For further comprehension of the invention, and of the objects and advantages thereof, reference will be had to the following description and accompanying drawing, and to the appended claims in which the various novel features of the invention are 15 more particularly set forth.

Fig. 1 of the drawing, is a perspective view of our improved refrigerating press.

Fig. 2 is a top plan view thereof.

Fig. 3 is a vertical sectional view taken on 20 the line 3—3 of Fig. 2.

As here embodied our improved refrigerating press, comprises a lower press member 10, of hollow cylindrical construction, and provided with a depending jaw shaped element 12, having an adjustable member 13, threadedly attached to and extending from the jaw shaped element 12, as a means of attaching the said lower press member 10, on a table, bench or the like. The bottom of element 10 has threadedly attached thereto, at its center, a connection 14, having an axial aperture 15, and a lower threaded extremity 16. It being understood that the upper portion 17 of the connection 14 extends within 25 the bottom element 11, and that its lower threaded extremity 16 extends beyond the bottom element 11, and is held in position by a nut 18 threadedly attached to the said connection.

40 The upper press member 19, of hollow cylindrical construction and having a top element 20, is provided with depending ears 21 suitably located to coincide with the ear 22 extending from the said lower press member 45 10, the said upper press member 19 being hinged to the said lower press member, as at 23, by a pin, or the like, located in the said ears 21 and in the ear 22. The upper press member 19 is also provided with a handle 24, depending therefrom, and opposite to the said ears 21, as a means of opening the said press members 19 and 11. The handle 24, has pivotally attached thereto, as at 25, a

latch 26, preferably U shaped, and adapted to engage the depending catch 27 of the 55 lower press member 11, when the said press members 19 and 11 are closed, and when the said latch 26 is pressed or forced inward, as a means of holding the said press members 60 in a closed position.

The top element 20 of the upper press member 19 is provided with a plurality of circular apertures, 20' comparatively small, and closely spaced. The support 28 has downward extended elements 29 and 30, and is attached to the top element 29, as at 31, by bolts, studs, or the like, and is adapted to slidably engage the upper portion 32, of the plunger 33, which is provided with a lower portion 34, extending through the said 70 top element 20, the plunger 33 is also provided with an enlarged portion 35, positioned so as to limit the said engagement of the lower portion 34. The superimposed spring 36, is positioned on the said plunger 75 33 so as to normally hold the lower portion 34 in the said engaged position. The upper portion 32, has a depending member 37 or pointer, suitably attached thereto, and located so as to register with the graduations 80 38 on the arm 39, or scale, which is attached to the said support 29.

The operation, or functioning of our improved device is as follows, a cartridge 40 or container, of cardboard, or any suitable 85 material, is placed in our improved device, as clearly shown in Fig. 3 of the accompanying drawing, so that the aperture 41, centrally located in the bottom 42, of the said cartridge 40 engages the upper portion 17 90 of the connection 14, a piece of loosely woven or compressible material 43 being placed below the said bottom 42 of the cartridge 40, a piece of semi-porous material 44 is placed 95 over the said cartridge, and the upper press member 19 is placed in a closed position, and locked by the latch 26. The lower threaded extremity 16 of the connection 14, is attached to a tank containing carbon dioxide (CO_2) under pressure, when the valve attached to 100 the said tank is opened, the said carbon dioxide will enter the cartridge 40, and will pass through same, and through the piece of semi-porous material 44, and through the 105 apertures 20' in the top element 20, the solid form of carbon dioxide, commonly called

dry ice, will be entrapped and compressed in the cartridge 40. It being further understood that the piece of compressible material 43, will act as a cushion, and that the said 5 plunger 33 will be raised, and that the said valve of the said carbon dioxide tank will be manually closed when the pointer 37 reaches the desired graduation 38 on the scale 39, depending upon the extent or 10 amount the dry ice is desired to be compressed.

While we have above described the preferred form, construction and arrangement of the several elements employed, it will be 15 understood that the device is, nevertheless, susceptible of considerable modification therein, and we therefore reserve the privilege of resorting to all such changes as may be fairly embodied within the spirit and 20 scope of the invention as claimed.

Having thus described our invention, what we claim as new and desire to protect by Letters Patent of the United States is as follows:

25 1. A refrigerating press, comprising a lower press member of hollow cylindrical construction, a jaw-shaped element depending from said lower press member, an adjustable member engaged in said jaw shaped 30 element, a connecting element threadedly engaged in said lower press member, an upper press member hingedly connected to said lower press member, a handle depending from said upper press member, said handle being positioned directly opposite the hinge of said press members, a latch pivoted to said handle, a catch depending from said lower press member, and engageable with said latch, said upper press member being 35 formed with a plurality of apertures, a support having downwardly extending elements attached to said upper press member, a plunger having its upper portion engaged in said support, the lower portion of said 40 plunger extending through said upper press member, an enlarged portion on said plunger to limit the downward motion of said plunger, a superimposed spring on said plunger, normally urging said plunger downward, a 45 pointer depending from the upper portion of said plunger, and an arm with graduations thereon attached to said support, and extending along the line of motion of said pointer.

50 55 2. A refrigerating press, comprising a lower press member of hollow cylindrical construction, a jaw shaped element depending from said lower press member, an adjustable member engaged in said jaw shaped 60 element, a connecting element threadedly engaged in said lower press member, an upper press member hingedly connected to said lower press member, a handle depending from said upper press member, said handle being positioned directly opposite the

hinge of said press members, a latch pivoted to said handle, a catch depending from said lower press member, and engageable with said latch, said upper press member being formed with a plurality of apertures, a support having downwardly extending elements attached to said upper press member, a plunger having its upper portion engaged in said support, the lower portion of said plunger extending through said upper press member, an enlarged portion on said plunger to limit the downward motion of said plunger, a superimposed spring on said plunger, normally urging said plunger downward, a pointer depending from the upper portion of said plunger, and an arm with graduations thereon attached to said support, and extending along the line of motion of said pointer.

3. A refrigerating press, comprising a lower press member of hollow cylindrical construction, a jaw shaped element depending from said lower press member, an adjustable member engaged in said jaw shaped element, a connecting element threadedly engaged in said lower press member, an upper press member hingedly connected to said lower press member, a handle depending from said upper press member, said handle being positioned directly opposite the hinge of said press members, a latch pivoted to said handle, a catch depending from said lower press member, and engageable with said latch, said upper press member being 90 formed with a plurality of apertures, a support having downwardly extending elements attached to said upper press member, a plunger having its upper portion engaged in said support, the lower portion of said plunger extending through said upper press member, an enlarged portion on said plunger to limit the downward motion of said plunger, a superimposed spring on said plunger, normally urging said plunger downward, a pointer depending from the upper portion of said plunger, and an arm with graduations thereon attached to said support, and extending along the line of motion of said pointer.

4. In a device of the class described, a lower press member, and an upper press member hinged thereto, said upper press member having a depending handle and a latch pivoted thereto, to engage a catch of the said lower press member, so as to hold the said press members closed, said upper press member having a top element provided with a plurality of apertures, said lower press member having a connection attached at the center of a bottom element of the said lower press member, a support having downward extended elements, and attached to the said top element, and adapted to slidably engage the upper portion of a plunger provided with a lower portion extending through

the said top element, said plunger provided with an enlarged portion, positioned to limit the said engagement of the said lower portion, a superimposed spring positioned on the said plunger so as to normally hold the said lower portion in the said engaged position, the said upper portion having a

pointer attached thereto, and located so as to register with graduations on an arm attached to the said support. ¹⁰

In testimony whereof we have affixed our signatures.
